(57) **CLAIM**

The ornamental design for a storage tray, as shown and described.

DESCRIPTION

FIG. 1 is a front perspective view of a storage tray, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is the perspective view of storage tray showing the lid closed.

The broken lines in the drawings illustrate the portions of the storage tray, which form no part of the claimed design.

1 Claim, 9 Drawing Sheets
